UNITED STATES PATENT OFFICE.

HARRY GEHMAN, OF PHILADELPHIA, PENNSYLVANIA.

DUSTPAN.

Application filed March 20, 1924. Serial No. 700,594.

To all whom it may concern:

Be it known that I, HARRY GEHMAN, a citizen of the United States, residing at Philadelphia, in the county of Philadelphia, 5 and State of Pennsylvania, have invented a new and useful Dustpan, of which the following is a specification.

This invention relates to an improved dust pan of the type which is most commonly 10 used in public buildings and the like for picking up dirt and trash, and which is usually provided with a hinged lid or cover adapted to be closed to retain the contents therein, so that the pan will be sanitary, and 15 the contents thereof will not be offensive to the by-standers.

The general object of the invention is to provide improved means for actuating the lid or cover, whereby it will be automatically 20 opened whenever the pan is set upon the floor for sweeping trash thereinto, but will always be closed by gravity whenever the pan is lifted from the floor.

The detailed construction of the invention 25 and its objects and advantages will be more particularly described in connection with the accompanying drawing, which illustrates the preferred form of the invention.

30 In the drawing:

Figure 1 is a perspective view of the invention resting upon the floor with its lid open.

Figure 2 is a side elevation of the invention 35 with the lid closed, but showing in dotted lines the position of the latter when open.

The dust pan, which forms the subject of my invention, is of the usual shape, comprising 40 a receptacle or body portion 5, which terminates at the front side in a mouth 6 having sloping side edges 7, and adapted to be closed by a lid or cover 8, which is hinged at 9 to the upper side of the receptacle. The 45 side edges of the lid 8 are extended to form down-turned flanges 10, which overhang the upper sloping edges 7 of the sides of the receptacle, and to these flanges the respective links 11 are pivotally connected by suitable pins or rivets 12. Links 13 have their 50 upper ends pivotally connected at 14 to the sides of the receptacle near the lower rear corners thereof, the lower ends of the links 13 being pivotally connected, as at 15, to the free ends of the links 11 to form toggles. A keeper 16 is secured to each side of the

receptacle and embraces one of the links, as 11, so that the toggle is constrained to move in a plane adjacent the side of the receptacle, but the keeper is elongated so as 60 to permit the link to swing in a longitudinal direction as the angle between the links of the toggle varies. A handle 17, substantially vertical, is secured in a socket 18 formed on the back side of the receptacle. 65

When the dust pan is being carried by means of the handle 17, the lid 8 will close by gravity to the position shown in full lines in Figure 2, and the toggles consisting of the links 11 and 13 will hang downwardly 70 below the bottom of the pan. Whenever the pan is set upon the floor, as indicated in Figure 1, and in dotted lines in Figure 2, the pivotal connections 15 of the toggles will first engage the floor, and cause the toggles to swing upwardly about the pivotal points 14, while the links 11 are guided in a vertical plane by the keepers 16. Thus, the lid 8 automatically opens whenever the pan is placed upon the floor to sweep dirt or trash 75 thereinto, but when it is lifted from the floor the lid is closed to retain the trash. It, therefore, prevents the dust from spreading and conceals the contents of the pan, the appearance of which might be objectionable 80 to by-standers or patrons. 85

It will be noted that a dust pan constructed according to my invention is simple in its construction, may be manufactured at a reasonable cost, and is entirely automatic in its operation. While I have shown and described the specific construction of the invention in its preferred form, it is to be understood that this is merely illustrative, and that various modifications may be 90 made in the size, proportion and general arrangement of the various elements without departing from the principles of the invention, or sacrificing any of its advantages. 95

What is claimed is:

1. A dust pan comprising a receptacle having a flat imperforate bottom, and a mouth with a hinged lid, links pivotally connected to the opposite sides of the lid and depending therefrom, other links pivotally connected at their inner ends to the free ends of the first-mentioned links and pivoted at their rear ends to the rear end of the receptacle, all of said links being arranged on the outside of the receptacle and movable at the sides thereof, and a rigid handle connected to the receptacle, whereby when 100

105

110

- the pan is being carried by the handle the lid will close by gravity and will be kept closed by the links at each side, said links hanging downwardly below the bottom of 5 the receptacle at an angle, and when the pan is set down on the floor, the links will engage the floor at the inner pivoted connections and cause the links to swing upwardly to open the lid.
- 10 2. A dust pan, comprising a receptacle having an upstanding handle and provided with a mouth having a hinged lid, said lid having its side edges extended to form downturned flanges which overhang the 15 sides of the receptacle, a pair of opposed links pivotally connected to the lid at opposite sides of the mouth, another pair of links pivotally connected at their rear ends to the

sides of the receptacle near its rear end, and pivotally connected at their front ends to 20 the free ends of the first-named links respectively, to form toggles which project below the bottom of the pan when the lid is closed, so as to be engageable by the floor to raise the lid when the pan is set thereon, 25 and a keeper at each side of the receptacle embracing one of the links of the toggle and constraining it to move in a plane adjacent the side of the receptacle, but permitting it to swing longitudinally of the receptacle as 30 the angle between the links of the toggle increases or diminishes.

In testimony that I claim the foregoing as my own, I have hereto affixed my signature.

HARRY GEHMAN,
